UNITED STATES PATENT OFFICE.

JOSEPH C. EARNSHAW, OF PHILADELPHIA, PENNSYLVANIA, ASSIGNOR TO SOLOMON SELIG, MORRIS A. KAUFFMAN, AND JOSEPH ELIAS, OF PHILADELPHIA, PENNSYLVANIA, TRADING AS MOSS ROSE MANUFACTURING COMPANY.

DOUBLE-FACED WOVEN FABRIC.

No. 881,386.

Specification of Letters Patent. Patented March 10, 1908.

Application filed June 14, 1907. Serial No. 378,942.

To all whom it may concern:

Be it known that I, JOSEPH C. EARNSHAW, a citizen of the United States, residing at Philadelphia, in the county of Philadelphia and State of Pennsylvania, have invented a new and useful Improvement in Double-Faced Woven Fabrics, of which the following is a full, clear, and exact description, reference being had to the accompanying drawing, which forms a part of this specification, and in which there is illustrated diagrammatically in section, taken in the direction of the warps—*i. e.*, transversely of the wefts—a fabric embodying features of the invention.

The object of my invention is to produce a double ply fabric, suitable for curtains, draperies, or the like. A fabric embodying the invention has as one of its plies a warp predominating cloth of known weave formed by the interweaving of warp-threads, and buried weft-threads, the warp-threads being sufficiently numerous to produce upon a ground, commonly known as a rib or a rep, (in which alternate warp-threads pass over and under the weft-threads) a figure, formed by warp-threads floating over weft-threads. The other ply of the fabric embodying the invention is a weft predominating cloth of known weave formed by heavy weft-threads and fine warp-threads; the fine warp-threads being only sufficiently numerous to, when passed alternately over and under the weft-thread, form a fabric. The weft-threads may also be used to form a figure, by floating them or some of them over two or more warp-threads, as may be required by the design. This ply may be further varied by the division of the warp-threads into alternate dark and light warp-threads, which in combination with the weft-threads, serve to produce figure effects, caused by the difference in shade, which the weft-threads assume, when bound,—as the design may require,—by either dark or light warp-threads; the warp of either color, which is not required for the use on the face, meanwhile floating between the two plies.

In practice I can use an equal number of weft-threads in both plies, or I may vary the proportionate number of the weft-threads in either ply as required by various qualities of cloths, which I may desire to produce.

I am enabled by the use of the weaver's art, to produce in the finished fabric the first ply 55 on the face, the second ply on the back; or their position may be reversed, the second ply on the face and the first ply on the back, as may be required by the design. The complete fabric is joined only at those points 60 where the two cloths intersect in passing from face to back or back to face and at all other points is two separate an independent fabrics forming as it were a series 65 of bags or pockets. In these two cloths, by reason of their independent nature, the number of weft threads per inch may be the same or may be varied in either cloth without affecting the other cloth. Furthermore the baglike or pocketed structure 70 imparts to the fabric qualities which especially adapt it for draping purposes.

The construction of my improved fabric may be readily understood by reference to the accompanying drawing.

The fabric in one ply is composed of the warp-threads A, and B, and the weft-threads F, and in sections 1, 3, and 4, it appears on the top or upper ply, while in section 2, it appears on the lower ply. This ply is a warp 80 predominating cloth in which the figure f is raised and, is formed by bringing the entire warp required for the figure to the face and permitting the weft to float on the back between the two plies and in which the 85 ground g, is formed or produced by interweaving alternate warp-threads with the weft-threads after the fashion of plain weaving. The other ply is composed of fine warp-threads C and D, and heavy weft-thread E, 90 and in sections 1, 3, and 4 it appears on the lower ply, while in section 2, it appears on the upper ply. In sections 1, and 2, I show the weft-threads in both upper and lower plies to be of equal number; in section 3, the lower 95 ply has only one half as many weft-threads as the upper ply; while in section 4, the upper ply has only one-half as many weft-threads as the lower ply. The proportionate number of the weft-threads in either ply in section 3, 100 and 4, may vary, as required by the various qualities of cloths. This ply is a weft-predominating cloth which may be plain woven, as at h, or figured by floating wefts as at m, over the warp which goes to the back between the plies.

Having now fully described my invention, what I claim and desire to protect by Letters Patent is:

A double ply drapery fabric formed by the combination of two cloths independent of each other in their construction and reversible in their relative positions and joined only by their intersections and whereof one is a weft predominating cloth and whereof the other is a warp predominating cloth in which the figure is raised by bringing the entire

warp to the face and permitting the weft to float between the two cloths and in which the ground is formed by interweaving alternate warp threads with weft threads, substantially as described.

In testimony whereof I have hereunto signed my name.

JOSEPH C. EARNSHAW.

In the presence of—

Wm. J. JACKSON,
K. M. GILLIGAN.
